(57) **CLAIM**

The ornamental design for a charger, as shown and described.

DESCRIPTION

FIG. 1 is a rear view of a charger, showing my new design; FIG. 2 is a front elevation view thereof;

FIG. 3 is a top plan view thereof;

FIG. 4 is a bottom plan view thereof;

FIG. 5 is a left-side elevation view thereof;

FIG. 6 is a right-side elevation view thereof; and,

FIG. 7 is a top, front, left side perspective view thereof.

The broken lines in the drawings depict portions of the

charger that form no part of the claimed design.
